UNITED STATES PATENT OFFICE.

JOHN HOPSON, JR., OF NEW LONDON, ASSIGNOR TO THE WATERBURY CLOCK COMPANY, OF WATERBURY, CONNECTICUT.

DESIGN FOR A CLOCK-CASE.

SPECIFICATION forming part of Design No. 23,697, dated October 16, 1894.

Application filed September 7, 1894. Serial No. 522,399. Term of patent 7 years.

To all whom it may concern:

Be it known that I, JOHN HOPSON, Jr., of New London, in the county of New London and State of Connecticut, have invented a new 5 Design for Clock-Cases; and I do hereby declare the following, when taken in connection with the accompanying drawings and the letters of reference marked thereon, to be a full, clear, and exact description of the same, and 10 which said drawings constitute part of this specification, and represent, in—

Figure 1, a view in front elevation of a clock-case embodying my design; Fig. 2, a view thereof in side elevation; Fig. 3, a plan 15 view of the case.

My invention relates to a design for clock cases, and consists in the configuration and ornamentation as hereinafter described and shown in the accompanying illustrations.

20 My newly designed clock case is tapering in general form, and has at its corners heavy inclined ribs A, which project beyond the planes of its front and sides, and each of 25 which is ornamented by a raised band of leaves A', the lower ends of the two ribs, flanking the front of the case, being turned inward to form scroll-like feet A². The front of the case contains a dial-opening B, which 30 is encircled by a band of beads or, as they are sometimes called, pearls B'. Below the said opening are two panels C, containing fleur-de-lis C'. The inner edges of the said panels are concave in form, and partially sur-

round a wreath D of leaves. Centrally above the dial-opening B there is a fan-like ornament E, the upper end of which stands alone and inclines slightly forward, as shown in Fig. 2. From the base of this ornament run simple scrolls E'. Each side of the case contains an oblong panel F, inclosing fleur-de-lis F'. Below this panel is arranged a wreath G, while above it are located three large conventional, foliated figures H, located at the three corners of a triangle. Above the upper of these figures is located another wreath I, reversed 45 in position from the wreath G, before mentioned.

The very top of the case is formed by a low, dome-like, rectangular piece K, ornamented with two lines of beads L, joining its 50 opposite corners, and with small sprays of flowers M located between the beads.

The detail features of the design are for the most part composed of those ornamental motives distinctive of the Empire style. 55

I claim—

The design for a clock case, substantially as herein shown and described.

In testimony whereof I have signed this specification in the presence of two subscribing witnesses. 60
